UNLOADER FOR COMPRESSORS

James H. Anderson, Easton, Pa., assignor to
 Ingersoll-Rand Company, New York, N. Y., a
 corporation of New Jersey

Application March 22, 1946, Serial No. 656,318

1 Claim. (Cl. 230—27)

1
 This invention relates to compressors, and more particularly to an unloader for compressors operated by constant speed drivers, such as synchronous electric motors, which are not readily adapted to actuate a compressor piston at different velocities for changing the capacity of the compressor.

One object of the invention is to equip the compressor with a durable unloading device that is reliable in action and requires a minimum of parts of simplified construction and which may be readily maintained with a minimum of attention to assure their efficient action throughout prolonged periods of service.

Other objects will be in part obvious and in part pointed out hereinafter.

In the drawings accompanying this specification and in which similar reference numerals refer to similar parts,

Figure 1 is a longitudinal elevation, partly broken away, of a portion of a compressor having the invention applied thereto.

Figure 2 is a view similar to Figure 1 showing a modified form of the invention.

Figure 3 is a transverse view taken through Figure 2 on the line 3—3.

Figure 4 is an elevation, in section, of a detail, and

Figure 5 is a transverse view taken through Figure 4 on the line 5—5.

Referring to the drawings and at first more particularly to Figure 1, 20 designates the compressor and 21 its casing which is bored to provide a compression chamber 22 the end of which is closed by a head 23.

Within the compression chamber is a reciprocating piston 24 for compressing the fluid medium, and in the wall of the compression chamber is an inlet valve 25 for controlling the flow of the fluid medium from an inlet chamber 26 into the compression chamber. In this form of the invention all the fluid discharged from the chamber 22 passes through a discharge port 27 into a clearance chamber 28, thence through a suitable discharge valve 29, a discharge chamber 30 and a conduit 31 to a storage receiver 32.

In accordance with the practice of the invention, communication between the compression chamber 22 and the clearance chamber 28 is controlled by a clearance control valve mechanism 33 that serves the additional function of unloading the compressor. The valve mechanism 33 comprises a casing 34 having an external flange 35 to seat upon the outer surface of the casing 21. The discharge port 27, and which is in con-

2
 stant communication with the compression chamber 22, is positioned in the inner end of the casing 34, and in the side of said casing is an opening 36 to open the interior of the casing 34 to the clearance chamber 28. On the inner surface of the end wall of the casing 34 is an upstanding flange 37 that encircles the port 27 and supports the valve mechanism 33 which is clamped against the flange 37 by a cover 38 that is pressed against the valve mechanism by a bolt 39 threaded into a plate 40 overlying the outer end of the casing 34.

The valve mechanism 33 comprises a pair of valve seats 41 and 42 that engage the flange 37 and the cover 38, respectively, and are secured together by screws 43. The major portions of the opposed surfaces of the valve seats 41 and 42 are inclined to define therebetween a V-shaped space 44 which is the operating range of a valve element 45 clamped between the valve seats adjacent the closed end of the space 44.

The inclined surfaces on the valve seats 41 and 42 constitute seating surfaces 46 and 47, respectively, for the valve 45 which, in a preferred form, comprises a plurality of spring-fingers 48 that control the adjacent ends of ports 49 and 50 in the valve seats 41 and 42. The valve element 45 is preferably constructed of a single straight plate so that the fingers 48 will occupy a mid-position in the space 44 when the valve is inactive.

The fingers are lifted against the seating surface 47 by pressure fluid flowing from the compression chamber 22 to the clearance chamber and are actuated in the opposite direction by pressure fluid supplied thereto from the storage receiver 32. Such pressure fluid is conveyed from the receiver by a conduit 51 connected to the bolt 39 which has a passage 52 extending therethrough to register with a port 53, in the cover 38, opening into the interior of the cover 38 which constitutes a pressure chamber 54.

The pressure value of the fluid thus introduced into the pressure chamber 54 is varied in accordance with variations in pressure, above a predetermined value, in the receiver: during partial load of the compressor, the pressure in the chamber 54 is varied progressively in inverse relation to progressive variations in pressure in the receiver; at full load the pressure in the chamber 54 is receiver pressure; and at no load the pressure in chamber 54 is atmospheric pressure. The regulator 55 performing this function is interposed between the branches 56 and 57 of the conduit 51. In the position of the regulator, as

3

shown in the drawing, the branch 57 is connected to the casing 58 at a lower elevation than the branch 56, and communication between the branches takes place through the bore 59 in the casing. The casing 58 is further provided with an exhaust port 60 located below the branch conduit 57 to afford communication between the bore 59 and the atmosphere.

Within the bore 59 is a reciprocatory valve 61 of the spool type having a pair of heads 62 and 63 which are so spaced with respect to each other that, in the position which the valve occupies normally, the head 63 will cover the exhaust port 60 and the head 62 will lie above the branch conduit 56 to permit of free communication between the branches 56 and 57 of the conduit 51. More specifically, the distance between the inner end surfaces on the heads 62 and 63 is equal to the distance between the upper edges (as viewed in Figure 1) of the port 60 and the port in the casing 58 registering with the branch conduit 56. Thus, as the head 62 moves downwardly to restrict the flow of compressed air into the bore 59 from the conduit 56, the head 63 simultaneously moves to uncover the port 60. The position of the valve 61 is determined by a spring 64 in the lower end of the casing 58 interposed between the valve and a spring seat 65 which may be raised or lowered, as by means of a screw 66, to condition the valve for controlling movement responsively to different pressures in the receiver 32.

On the upper end of the valve is a stem 67 that is connected to the central portion of a flexible diaphragm 68 that is clamped between the casing 58 and a cover 69 of cup-shape, the interior of which constitutes a pressure chamber 70 and is in communication with the receiver through a conduit 71.

In operation, and assuming the pressure within the storage receiver 32 to be below the predetermined maximum value for which the regulator 55 has been set, all the fluid medium compressed by the piston 24 is discharged through the port 27 and the valve mechanism 33 into the clearance chamber 28 whence it passes through the discharge valve 29 and the associated channels into the receiver 32.

The fluid passing through the valve seat 41 actuates the valve 45 against the seating surface 47 and holds it in that position until the piston 24 begins its suction stroke. At this point in the cycle of operation the pressure within the pressure chamber 54, and which is conveyed thereto from the receiver by the conduit 56, will return the valve fingers 48 to the seating surface 46 and cut-off communication between the clearance chamber 28 and the compression chamber 22. The inlet valve 25 will then open to admit fluid into the compression chamber from the inlet chamber 26.

The valve mechanism 33 will continue to operate in the manner described and communication will exist uninterruptedly between the storage receiver 32 and the pressure chamber 54 until the receiver pressure predominates over the force exerted by the spring 64. When this predetermined maximum value is attained the fluid acting against the diaphragm 68 will depress the valve 61 to reduce the flow of pressure fluid into the bore 59 and to uncover the exhaust port 60. The pressure chamber 54 will then be in communication with the atmosphere thereby reducing somewhat, depending on the degree of opening of the port 60 and the port registering with line 56, the

pressure in the chamber 54; and thereafter the valve fingers 48 will remain seated against the seating surface 47 until the pressure in the compression chamber 22 equals that prevailing within the chamber 54. The inherent resiliency of the valve fingers 48 will then cause them to snap back toward the seating surface 46. This movement of the valve fingers will take place at any point in the suction stroke of the piston at which the pressures within the clearance and pressure chambers equal each other, and when, during this stroke the pressure of the fluid in the compression chamber falls below that prevailing in the inlet chamber 28 the inlet valve 25 will admit a new charge of fluid into the compression chamber.

The point in the suction stroke at which the valve action occurs is controlled by the degree of opening of the port 60 and of the port in the casing 58 registering with the conduit 56—the degree of opening of said ports is, in turn, dependent on the receiver pressure. That is, as the receiver pressure progressively increases, above the aforesaid predetermined value, the valve 61 is actuated in accordance with this increase to progressively throttle the flow of pressure fluid from the receiver 32 through the conduit 56 and progressively increase the degree of opening of the port 60. With this arrangement then, as the pressure within the receiver 32 increases above some predetermined value, the regulator 55 acts to decrease, in proportion, the pressure in the chamber 54. The converse function also occurs—as the receiver pressure decreases towards said predetermined value, the valve 61 moves to uncover the downstream end of the conduit 56 and restrict the flow through the exhaust port 60, thereby increasing the pressure within the chamber 54. Thus the regulator 55 acts in response to variations in receiver pressure, above said predetermined value, to vary in inverse proportion the pressure in the chamber 54.

Whenever the pressure within the storage receiver 32 falls below that exerted by the spring 64 the said spring will shift the valve 61 to reestablish communication between the branch conduits 56 and 57 and to close the exhaust port 60. The compressor is then again conditioned for the delivery of its entire discharge output to the storage receiver.

The modified form of the invention shown in Figures 2 and 3 differs from that previously described in the respects that a discharge valve mechanism 72, or mechanisms, and which may be of any suitable type, serves as the sole flow controlling element between the compression chamber and the storage receiver, and the valve mechanism 33 serves the single function of controlling the compressor load.

During the pumping action of the piston 24 compressed fluid passes both through the discharge valve 72 and through the valve mechanism 33. In view of the small capacity of the clearance chamber as compared with the storage receiver and the channels leading thereto the predetermined maximum pressure which it is intended to maintain within the storage receiver is quickly reached in the clearance chamber and will normally be reduced only by such amounts as may pass from the pressure chamber 54 through the conduit 51 to the storage receiver during the suction stroke of the piston and at which time the ports 50 will be uncovered. The valve mechanism 33 will then operate in the

same manner as in the form of the invention previously described. On each compression stroke of the piston 24, the valve fingers will be lifted by the fluid in the compression chamber 22 and enough fluid will pass into the clearance chamber 28 to compensate for the slight reduction incident to the flow of fluid from the clearance chamber to the storage receiver through the conduit 51.

When the predetermined maximum pressure is reached in the storage receiver 32 the pressure fluid in the pressure chamber 70 will act against the diaphragm 68 and depress the valve 61, thereby conditioning the valve mechanism 33 to perform its load-controlling function.

15

I claim:

In an unloader for a compressor, a casing having a compression chamber, a piston therein, a receiver for the fluid compressed by the piston, a discharge valve for controlling communication between the compression chamber and the receiver, a clearance chamber, a clearance control valve means to control communication between the compression chamber and the clearance chamber comprising a cage having a pressure chamber and opposed seating surfaces, a valve in the cage to cooperate with one seating surface for controlling communication between the compression and clearance chambers

5

and to cooperate with the other seating surface for controlling communication between the pressure chamber and the clearance chamber, the third said valve being constantly subjected to the pressure prevailing in the compression chamber for moving the third said valve away from said one seating surface to establish communication between the compression and clearance chambers, means for supplying pressure fluid from the receiver to the pressure chamber for returning the third said valve to said one seating surface, and means acting responsive to pressure in the receiver for controlling the pressure value of the fluid in the pressure chamber.
